(57) **CLAIM**

The ornamental design for a fitness article, as shown and described.

DESCRIPTION

FIG. 1 is a front view of a fitness article showing my new design;

FIG. 2 is a top view of the fitness article shown in FIG. 1;

FIG. 3 is a left side view of the fitness article shown in FIG. 1,

the right side view being a mirror image thereof;

FIG. 4 is a front perspective view of the fitness article shown in FIG. 1; and,

FIG. 5 is a rear perspective view of the fitness article shown in FIG. 1.

The broken lines showing of the screws, rivets and top opening illustrates portions of the fitness article which forms no part of the claimed design.

1 Claim, 3 Drawing Sheets

FIG. 1

FIG. 2

FIG. 3

FIG. 4

FIG. 5
